George William Mather

UNITED STATES PATENT OFFICE.

ABBOT AUGUSTUS LOW, OF BROOKLYN, NEW YORK.

DESIGN FOR A CHANGE-HOLDER.

SPECIFICATION forming part of Design No. 23,522, dated July 31, 1894.

Application filed July 9, 1894. Serial No. 517,011. Term of patent 14 years.

To all whom it may concern:

Be it known that I, ABBOT AUGUSTUS LOW, a citizen of the United States, residing in the city of Brooklyn, in the county of Kings and State of New York, have invented and produced a new and useful Design for Change-Holders, of which the following is a specification, reference being had to the accompanying drawings.

10 Figure 1, is a plan of the design; Fig. 2, a transverse section thereof, upon plane of line x, x , Fig. 1.

The leading feature of my design consists in a series of smaller pockets or depressions 15 arranged in a circle around a larger central pocket or depression, a raised circular rim surrounding the whole.

A, is the body, the top of which is circular, and is formed with the annular ridge or rim a .

B, is a comparatively large cup or depression formed in the top of the holder, and b, b , are a series of smaller cups or depressions arranged around the central cup B. The smaller cups b, b , are equi-distant, and are formed concentrically around the central cup. 25

What I claim is—

The design for a change holder herein shown and described.

ABBOT AUGUSTUS LOW.
